RECEIVING AND SIGNALING DEVICE FOR WRITTEN MESSAGES

Dennis J. Lowery and Robert E. Merchant, Grand Junction, Colo., assignors to Dixson, Inc., Grand Junction, Colo.

Filed May 2, 1972, Ser. No. 249,757

Term of patent 14 years

Int. Cl. D14—02

U.S. CL. D74—1 R

FIG. 1

FIG. 2

FIG. 3

FIG. 4

FIG. 5

FIG. 1 is a perspective view of our design of a receiving and signaling device for written messages;

FIG. 2 is a front elevational view thereof;

FIG. 3 is a back elevational view thereof;

FIG. 4 is a right side elevational view thereof and the left side elevational view would be the same; and

FIG. 5 is a top view thereof, and the bottom is a plain flat surface.

We claim:

The ornamental design for a receiving and signaling device for written messages, as shown and described.
